EQUILIBRATOR

Joseph F. Joy, Claremont, N. H.

Application March 3, 1942, Serial No. 433,139

7 Claims. (Cl. 267—1)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a hydro-pneumatic device and more particularly to a hydro-pneumatic equilibrator intended to balance the weight of heavy mechanisms such as artillery weapons.

In devices of this character it is desirable that a liquid pressure transmitting medium be used which may perform the additional functions of lubricating the cylinder walls and facilitating the packing or sealing of piston and piston rod. It is also desirable that some compressed gaseous medium be provided to absorb and balance the loads applied to the pressure transmitting medium. At the same time to avoid undesirable absorption of gas in the liquid medium a separation should be maintained between the liquid and gaseous media while providing for a free exchange of pressure therebetween.

It is therefore an object of this invention to provide a hydro-pneumatic equilibrator in which a practically frictionless separation may be maintained between liquid and gas.

It is a further object to provide an equilibrator of the character discussed above which may be conveniently and economically manufactured.

It is another object to provide an equilibrator having substantially frictionless separating means between the liquid and gas which will be immune to damage in the event of the leakage of any considerable quantity of the liquid medium.

The exact nature of the invention as well as other objects and advantages thereof will clearly appear from a description of a preferred embodiment as shown in the accompanying drawing in which:

Fig. 1 is a longitudinal sectional view of an equilibrator constructed according to my invention and shown in retracted position.

Fig. 2 is a similar view on a reduced scale showing the equilibrator in fully extended position.

Figure 3 is a cross sectional view on the line 3—3 of Fig. 1.

Figure 4 is a similar view on the line 4—4 of Fig. 2.

Referring to the drawing by characters of reference there is shown a main cylinder 1 having within and concentric therewith a second cylinder 2 of less length than the cylinder 1. A cylinder head 3 is provided with an internally threaded portion 4 adapted to be secured to the end of the cylinder 2 and to act as a support and

closure therefor. A portion 5 of the head 3 is provided with a shoulder 6 and external threads adapted to engage the end of the main cylinder 1. A passage 7 formed through the head 3 communicates with the space between the cylinders 1 and 2 and an air valve 8 is provided at the outer end of the passage 7. A fitting 9 may be provided on the cylinder head to enable the equilibrator to be attached to the device to be balanced. A centrally apertured diaphragm 10, received within the cylinder 1 and having grooves 11 in its cylinder engaging portion, is provided with an internally threaded portion 12 adapted to engage the inner end of the cylinder 2. A piston 13 slidable in the cylinder 2 is provided with packing 14 which may be retained by a packing nut 15. A piston rod 16 is secured to the piston and extends beyond the opposite end of the cylinder 1. A cylinder head 17 is provided for the last mentioned end of the cylinder 1 and has formed therein a centrally located aperture for the passage of the piston rod 16. A packing gland comprising packing 18 and a packing nut 19 prevents the escape of oil along the piston rod. A fitting 20 on the end of the piston rod may be utilized to connect the equilibrator to the device to be balanced and a bellows-like member 21 secured at one end to the fitting 20 and at the other end to the packing nut 19 surrounds the piston rod and protects its exposed portions from dust or other abrasive material. A passageway 22 is formed through the cylinder head 17 and an oil filler valve 23 is secured therein.

A secondary cylinder head 24 has a central aperture through which the piston rod passes and may be secured in the cylinder in spaced relation to the cylinder head 17 by means of a ring 25 of rubber-like packing material compressed between the angular shoulder 26 on the secondary cylinder head and a similar shoulder 27 on a ring member 28 drawn into engagement with the packing ring by bolts 29 engaging the secondary cylinder head. Engaging internal threads in the central apertures of the secondary cylinder head 24 and the diaphragm 10 and extending therebetween is a tube 30 having a plurality of small holes 30a piercing its wall in the section between the diaphragm and secondary cylinder head. An expandible tube 31 of natural or synthetic rubber or other material having rubber-like properties surrounds the pierced tube 30 and is provided with a bead-like flange 32 at each end. Annular channels 33 complementary in shape to the flange 32 are provided in the faces 55 of the diaphragm and secondary cylinder head

for the reception of the flanges 32. A pair of similar flanged members 34 are secured to the diaphragm 10 and secondary cylinder head by means of screws 35 and are provided with an annular portion 36 adapted to engage the bead-like flange 32 and compress the same into the channel 33 forming a gas and liquid tight joint. Portions 37 and 38 of the flanged members diverge from the expandible tube 31. Secured to the portion 38 of one of the flanged members by welding or other convenient means and engaged over the portion 37 of the other flanged member is a metallic tube 39 provided with a plurality of small apertures 39a.

In the use of the equilibrator oil or other convenient liquid may be introduced through the filler valve 23 preferably with the equilibrator in the position shown in Fig. 2 until the expandible tube 31 has been expanded and the space therein as well as the space between the cylinder head 17 and the secondary cylinder head 24 have all been completely filled with fluid and purged of imprisoned air bubbles. Through the valve 8 air or other compressible fluid may be introduced into the main cylinder and will surround the inner cylinder and expandible tube but will be positively separated from the liquid contained therein. Sufficient gas will be introduced to support the unbalanced load connected to the fittings 9 and 26, thus permitting the load to be moved readily in either direction with a minimum expenditure of energy. It will be obvious that, as the load is moved in a direction tending to extend the equilibrator, the piston will be drawn through the cylinder and will displace the liquid contained therein through the apertures 39a in the tube 39 to expand the expandible tube 31 against the pressure of the surrounding gas. In the event of the leakage of any considerable quantity of oil there will be no escape of gas and no possibility of destruction of the expandible tube as the tube will be pressed into engagement with the tube 39 and will act as a valve in closing the apertures 39a. The provision of a similar apertured tube exterior to the expandible member serves to protect the expandible tube by restraining bulges or other tendencies toward non-uniform expansion.

Obviously a device of this type is not limited in its utility to use as an equilibrator for a gun but may be used in any location requiring a resilient support in the nature of a spring the resistance of which may be conveniently regulated by the regulation of the pressure of the air confined. It should be noted that the only portions of the apparatus requiring surface finishing are of simple and readily accessible form and that highly finished surfaces have been reduced to a minimum. Such a construction is economical to manufacture and simple to maintain in the field.

I claim:

1. An equilibrator comprising a cylinder having an open end, a piston in said cylinder, a piston rod secured to said piston extending through the open end of said cylinder, a jacket secured about the open end of said cylinder extending therefrom to surround at least a part of the length of said piston rod extending from said cylinder, a packing gland in said jacket through which said

10 piston rod is slidable, an expandible tube of rubber-like material secured at one end to the open end of said cylinder and at the other end to said jacket in surrounding relation to said piston rod, a liquid contained in said cylinder and tube, and gas under pressure contained between said jacket and said tube, said gas being subject to further compression as said piston rod is withdrawn from said cylinder.

2. In an equilibrator as described in claim 1, a perforated metallic tube inside said expandible tube and supported at the ends thereof whereby said metallic tube will support said expandible tube in the event of leakage of fluid from said cylinder.

3. In an equilibrator as described in claim 1, a perforated metallic tube surrounding said expandible tube and supported at the ends thereof whereby said expandible tube may be supported against any tendency to localized abnormal expansion.

4. An equilibrator as described in claim 1, a head in the end of said cylinder remote from said open end, an enlarged rim on said cylinder head, and means by which an end of said jacket may be secured to said rim.

5. An equilibrator comprising a cylindrical jacket, closure means for an end of said jacket, a cylinder in said jacket secured to said closure means in coaxial relation with said jacket, a piston in said cylinder, a packing gland in the end of said jacket opposed to said closure means, a piston rod extending through said gland into secured relation with said piston, a centrally apertured secondary closure secured in the end of said jacket adjacent said packing, an expandible tube of rubber-like material secured at one end to said cylinder and at the other end to said secondary closure in surrounding relation to said piston rod, a liquid contained in said cylinder and the space within said expandible tube, and a compressed gas contained in said jacket, said gas being subject to further compression as said piston is withdrawn and the expandible member is expanded by the displaced liquid.

6. An equilibrator as described in claim 5 and a pair of perforated metallic tubes supported in coaxial relation with said expandible tube, one of said perforated tubes being inside said expandible tube and one of said perforated tubes being outside said expandible tube whereby said expandible tube may be supported against any tendency to abnormal deformation.

7. An equilibrator comprising a cylinder, a piston in said cylinder, a piston rod extending without the cylinder, an expandible tube of rubber-like material surrounding said rod and secured to an end of said cylinder, closure means for the end of said expandible tube, a packing gland in said closure means through which said piston rod is slidable, a jacket surrounding said expandible tube and secured at one end to said closure means and at the other end to said cylinder, compressed gas in said jacket, and liquid in said cylinder and said expandible tube whereby said gas may be further compressed as said liquid is displaced by said piston.

JOSEPH F. JOY.
